The ornamental design for a tissue and membrane puncher for periodontal plastic surgery and regenerative procedures substantially as shown and described.

DESCRIPTION

FIG. 1 is a top, left-side perspective view of the complete tissue and membrane puncher for periodontal plastic surgery and regenerative procedures.

FIG. 2 is a bottom, right-side perspective view of the complete tissue and membrane puncher for periodontal plastic surgery and regenerative procedures.

FIG. 3 is a top-side view thereof;

FIG. 4 is a bottom-side view thereof;

FIG. 5 is a right-side view thereof;

FIG. 6 is a left-side view thereof;

FIG. 7 is a front-side view thereof;

FIG. 8 is a rear-side view thereof;

FIG. 9 is a top, left-side perspective view of the 1st member of tissue and membrane puncher for periodontal plastic surgery and regenerative procedures.

FIG. 10 a bottom, right-side perspective view of the 1st member of tissue and membrane puncher for periodontal plastic surgery and regenerative procedures.

FIG. 11 is a top, left-side perspective view of the 2nd member of tissue and membrane puncher for periodontal plastic surgery and regenerative procedures; and,

FIG. 12 a bottom, right-side perspective view of the 2nd member of tissue and membrane puncher for periodontal plastic surgery and regenerative procedures.
